United States Patent

Des. 241,955
Patented Oct. 19, 1976

241,955

BOWLING TROPHY ACCESSORY

Paul Pisani, Chicago, Ill., assignor to Chicago Trophy &
Award Co., Chicago, Ill.

Filed July 11, 1975, Ser. No. 595,282

Term of patent 14 years

U.S. Cl. D11—164   Int. Cl. D11—02

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a bowling trophy accessory showing my new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a perspective view of a bowling trophy accessory showing a second embodiment of my new design;

FIG. 8 is a front elevational view thereof;

FIG. 9 is a rear elevational view thereof;

FIG. 10 is a perspective view of a bowling trophy accessory showing a third embodiment of my new design;

FIG. 11 is a front elevational view thereof;

FIG. 12 is a rear elevational view thereof;

FIG. 13 is a perspective view of a bowling trophy accessory showing a fourth embodiment of my new design;

FIG. 14 is a front elevational view thereof;

FIG. 15 is a rear elevational view thereof;

FIG. 16 is a left side elevational view thereof;

FIG. 17 is a top plan view thereof;

FIG. 18 is a bottom plan view thereof;

FIG. 19 is a perspective view of a bowling trophy accessory showing a fifth embodiment of my new design; and

FIG. 20 is a perspective view of a bowling trophy accessory showing a sixth embodiment of my new design.

Aside from the variation in top-mounted legends and digit display panels, the embodiments illustrated in FIGS. 19 and 20 have substantially the same configuration as that shown in FIGS. 13-18.

I claim:

The ornamental design for a bowling trophy accessory, substantially as shown and described.
